UNITED STATES PATENT OFFICE.

JOHN A. THOMAS, OF MILLVILLE, FLORIDA.

HAMMER.

SPECIFICATION forming part of Letters Patent No. 757,071, dated April 12, 1904.

Application filed July 15, 1903. Serial No. 165,548. (No model.)

To all whom it may concern:

Be it known that I, JOHN A. THOMAS, a citizen of the United States, residing at Millville, in the county of Washington and State of Florida, have invented a new and useful Hammer; and I do hereby declare the following to be a full, clear, and exact description of the invention, such as will enable others skilled in the art to which it appertains to make and use the same.

The invention relates to improvements in hammers, and has for its object to improve the construction of that class of hammers which are provided with an extensible fulcrum-bar or plunger adapted to coöperate with the claw of the hammer for enabling long nails to be extracted with ease and without bending them, whereby the extracted nails may be readily used over again.

A further object of the invention is to increase the strength and durability of the hammer and to facilitate the replacement of a broken handle by a new one by arranging the extensible fulcrum-bar or plunger independently of the handle and the eye of the hammer and by mounting the said fulcrum-bar or plunger entirely within the hammer-head.

With these and other objects in view the invention consists in the construction and novel arrangement of parts hereinafter shown, described, and claimed.

In the drawings forming part of this specification, and in which like numerals of reference designate corresponding parts, Figure 1 is a perspective view of a hammer constructed in accordance with this invention. Fig. 2 is a longitudinal sectional view of the same. Fig. 3 is a similar view on the line 3-3 of Fig. 2. Fig. 4 is a detail sectional view on the line 4-4 of Fig. 2.

Referring to the drawings, 1 designates a hammer-head provided with a claw 2 and having an elongated eye 3, adapted to receive a handle 4 of the ordinary construction. The hammer-head is provided at one side of the eye, at a point between the same and the claw, with a longitudinal opening 5, extending substantially the entire length of the eye and receiving an extensible fulcrum-bar or plunger 6. The opening 5 is enlarged at its upper end

7 to receive the head 8 of the fulcrum-bar, which is extensible and which is adapted to project beyond the hammer-head to form a fulcrum, whereby long nails may be readily extracted without bending them, thereby enabling such extracted nails to be used over again. The plunger or fulcrum-bar, which is rectangular in cross-section, is automatically moved outward by a coiled spring 9, located in the inner portion of the opening 5 and interposed between the inner end wall of the same and the inner end of the fulcrum-bar or plunger, whereby the coiled spring will be compressed when the fulcrum-bar is forced inward. The fulcrum-bar is provided at one side with a series of notches 10, adapted to be engaged by a transversely-disposed spring-actuated dog 11, mounted in a slot or recess 12 and pivoted between its end by a pin 13 or other suitable fastening device. The dog is provided at its engaging end with a projecting portion or tooth for engaging the notches, and a spring 14 is adapted to throw the other end of the dog outward. The outwardly-projecting end which extends from one side of the hammer-head is located contiguous to a lug 15, which forms a guard and which is adapted to prevent the dog from being accidentally operated by coming in contact with the supporting-surface or other objects when the hammer is laid down. When the dog is depressed and its tooth carried out of engagement with the fulcrum-bar or plunger, the latter is forced outward by the spring and may be locked at any adjustment by the dog, which when released reengages the fulcrum-bar or plunger. The outward movement of the fulcrum-bar or plunger is limited by a stop 16, consisting of a fastening device mounted on and extending through one side of the hammer-head and projecting into a longitudinal groove 17 in one side of the fulcrum-bar or plunger. By this construction the fulcrum-bar is prevented from entirely leaving the hammer-head when the dog is depressed.

It will be seen that the fulcrum-bar or plunger and the means for operating the same are located entirely within the hammer-head and beyond the eye of the same, and that the eye is adapted to receive the ordinary handle,

which is not weakened by the mounting of the fulcrum-bar or plunger on the hammer. It will also be apparent that the fulcrum-bar or plunger will not interfere with the removal of 5 the broken handle or with the substitution of a new handle for a broken one.

What I claim is—

In a device of the class described, the combination of a hammer-head provided at one 10 side of its eye with an opening, said hammer-head being also provided at one side with a slot or recess and having a projection at one end thereof, forming a guard, a spring-actu-

ated fulcrum-bar or plunger, located within the opening, and a spring-actuated dog mounted in the slot or recess and having an extended end located adjacent to and flush with the projection, whereby the dog is prevented from being accidentally operated in the use of the hammer, substantially as described. 15 20

In testimony whereof I have hereto affixed my signature in the presence of two witnesses.

JOHN A. THOMAS
